UNITED STATES PATENT OFFICE

FREDERICK E. TURNER, OF KANSAS CITY, MISSOURI

BASE FRAME FOR ELEVATOR MACHINES

Application filed October 30, 1926. Serial No. 145,217.

My invention relates to elevator machines and more particularly to a new and improved base member for elevator machines.

It is a purpose of my invention to provide a base frame for elevator machines that will not transmit vibration of the motor or other driving means for the traction sheave to the supporting means upon which the base member is mounted. Such supporting means are, 10 ordinarily, beams which form part of the framework of a building or are mounted in some manner upon the framework of a building so that vibration set up by the motor causes undesirable vibration of the building. 15 By providing a base member for the motor, the traction sheave and the interposed movable parts, which is provided with a vertically extending portion or web portion having open portions therein, said openings prevent 20 the transmission of the vibration from the motor and other parts located on the upperside of the base member to the supporting means on the lower side of the base member.

It is a further purpose of the invention to 25 provide a base member for the motor, the traction sheave, the brake and the reduction gearing, which is common to all these parts, said base member being preferably made of a single piece comprising a metal casting and 30 being preferably provided with upstanding portions which form bearing supports for the motor driven shaft and traction sheave, and one of which also forms a portion of the housing for the reduction gearing.

35 Other objects and advantages of the invention will appear as the description of the accompanying drawings proceeds. However, I desire to have it distinctly understood that I do not intend to limit myself to the exact 40 details shown or described, but that I intend to include as part of my invention all such obvious changes and modifications of parts as would occur to a person skilled in this art and as would fall within the scope of the 45 claims.

In the drawings:

Fig. 1 is a perspective view of an elevator machine, showing my improved base member in use.

50 Fig. 2 is a perspective view of my improved

base member, as viewed from the opposite side thereof.

Fig. 3 is a section thereof taken on the line 3—3 of Fig. 2, and

Fig. 4 is a section thereof taken on the line 4—4 of Fig. 2.

Referring in detail to the drawings:

My improved base member is mounted on any suitable support such as the parallel beams 10 which may be I-beams and may 60 form a portion of the building frame in which the elevator is located. Said base member preferably comprises a longitudinally extending arm 11 and a laterally extending portion 12 at one end of the arm 11. Mounted 65 upon the end of the arm 11 remote from the laterally extending portion 12 of the frame is the motor 13 which is provided with feet 14 which are supported upon the longitudinally spaced upper flanges 15 and 16 of 70 the arm 11.

A brake mechanism 18 is mounted between the motor 13 and the laterally extending portion 12 of the frame in the usual manner, 75 said brake mechanism being mounted upon the supporting members 19 which are secured to the laterally extending flanges 20 and 21 on the arm 11 of the base member, being secured thereto in any suitable manner as by means of the securing members 22 and being 80 provided with shims 23 between the supporting members 19 and the flanges 20 and 21 so as to properly align the brake mechanism 18 with the other parts of the device.

The arm 11 of the framework is preferably 85 provided with upper and lower flanges 24 and 25 which are narrower than the laterally extending flanges 15, 16, 20 and 21, and a web portion 26 between the upper and lower flanges 24 and 25 thus producing an integral 90 I-beam-like base member. The web portion is preferably provided with a plurality of openings 27 therein, said openings being of such a shape and size as to occupy a large portion of the space between the laterally 95 extending, strengthening webs 28, 29, 30 and 31 which are aligned substantially with the flanges 15, 16, 20 and 21 respectively. The strengthening web portions 28, 29, 30 and 31 increase in width from the flanges 15, 16, 20 100

and 21 to the flange 25, merging with said flange at the lower ends thereof. The web portion 26 is provided with thickened portions or ribs 32 surrounding the openings 27 to strengthen said web portions adjacent said openings. The lower flange 25 of the arm 11 is preferably provided with thickened portions forming transversely extending ribs 33, 34, 35 and 36 which 5 align substantially with the flanges 15, 16, 20, and 21 respectively, thus providing spaces 37 between the flange 25 and the upper flange of the beam 10 upon which the arm 11 is mounted, aligning substantially with the 10 openings 27 in the web 26. The weight of the motor 13 and the brake mechanism 18 is thus directly supported upon the beam 10, but a very small portion of the weight of these 15 parts being applied to the web portions where the openings 27 in the web 26. The weight of the motor 13 and the brake mechanism 18 is thus directly supported upon the beam 10, but a very small portion of the weight of these parts being applied to the web portions where 20 the openings 27 in the web 26. The weight of the motor 13 and the brake mechanism 18 is thus directly supported upon the beam 10, but a very small portion of the weight of these parts being applied to the web portions where 25 the openings 27 in the web 26. The weight of the motor 13 and the brake mechanism 18 is thus directly supported upon the beam 10, but a very small portion of the weight of these parts being applied to the web portions where not to the building.

The laterally extending portion 12 of the base member is made integral with the arm 11 and comprises a pair of transversely extending members having the upper flanges 38, the lower flanges 39 and the web portions 40 between said flanges. The web portions 40 of the transversely extending members 35 forming a part of the laterally extending portion 12 of the base member are preferably imperforate and are connected at the outer ends thereof by means of a longitudinally extending member having a web portion 41 and the upper flange 42 and lower flange 43. The web portion 41 is provided with an elongated opening 44 therein, similar to the openings 27 and is surrounded by a thickened portion or strengthening rib 45. The inner 40 ends of the transversely extending members are preferably connected to each other and with the arm 11 of the base member by means of a longitudinally extending portion having a web portion 46 provided with an elongated opening 47 and surrounded by a thickened portion or strengthening rib 48 and having furthermore the upper flange 49 and the lower flange 50. The outer end of the laterally extending portion 14 of the base member 50 has a bearing standard 51 integral therewith, said base member being provided with strengthening ribs 53 spaced slightly from the corners of the frame and in alignment substantially with the central portions of the lower ends 52 of the member 51. Said bearing support is provided with a bearing portion 56 for the traction sheave shaft 57. The laterally extending portion 12 of the frame 60 is preferably provided with thickened portions or feet 58 substantially in vertical alignment

70 with the ribs 53, thus providing a space at 59 between said feet. The web portion 41 thus carries but a very slight portion of the load, especially at the opening 44 thereof, the major portion of the load being transferred directly to the beam 10 through the reinforced corner portions of the base.

Extending upwardly from the portion of the base that connects the laterally extending portion 12 thereof and the longitudinally extending arm 11 are the obliquely extending frame portions 60 and 61 providing an opening 62 that is substantially aligned with the opening 47 in the web portion 46. The lower ends of said frame portions 60 and 61 are integral with the flange 49 and have the thickened portions 65 of the flange 50 substantially aligned therewith so that the major portion of the load supported by the vertically extending frame member thus formed is transferred to the supporting surface with which the feet 65 engage, through said feet, and but a very small portion of the load is carried by the web 46 where the opening 47 occurs therein. Surmounting the members 60 and 61 is a housing and bearing member 63 having the strengthening ribs 64 and the flanges 66 to which bearing members for the motor driven shaft are secured. Cooperating with the member 63 is a cap member 67 forming therewith a reduction gear housing said members 63 and 67 being provided respectively with bearing portions 69 and 70 for the shaft 57. The usual traction sheave 71 is mounted on the shaft 57 in the usual manner and is driven in the usual manner through the reduction gearing contained in the housing formed by the members 63 and 67.

It has been found that with the arrangement described, substantially all the vibration of the motor 13 and the other rotating parts carried by the angular base member, which, it will be noted, is substantially L-shaped, is eliminated by providing the openings 27, 44, and 47 in the web portions of the base member as described above, these openings preventing the transmission of the vibration of the said parts to the supporting members 10. At the same time, due to the provision of the strengthening ribs and strengthening webs, the strength of the base member as a whole is not materially affected by the provision of said openings.

What I claim and desire to secure by Letters-Patent is:—

1. In combination with spaced beams, a base frame comprising a longitudinal body member supported wholly by one of the beams and having an integral, outriding, lateral extension at one end of the body member supported at its free end on the other beam.

2. A base frame of the character described including a web having top and bottom

flanges and spaced openings, lateral riser webs integral with the body web and flanges located between said openings and downwardly extending transverse longitudinally spaced ribs integral with the web and bottom flange in substantial alignment with the riser webs for transferring weight of the frame and its load through the solid portions of said body web and through the riser webs 10 and ribs to a supporting base.

3. A base frame of the character described including a vertical web, having spaced openings and lateral bottom flanges, and having longitudinally spaced top flanges extending laterally from the solid portions of the web between the openings, riser webs integral with the body web and the top and bottom flanges, and longitudinally spaced transverse ribs on the body web and bottom flanges 15 beneath the riser webs.

4. A base frame for elevator machines comprising a single metal casting including a longitudinal arm adapted to support the motor and the brake mechanism of said machine, a lateral arm comprising spaced portions, and laterally spaced standards extending upwardly respectively from the longitudinal arm and the outer end of the lateral arm.

5. A base frame for elevator mechanism comprising a one-piece base member including a longitudinal I-beam-like portion and a portion extending laterally from one end of the longitudinal portion comprising spaced I-beam-like members, a bearing member integral with the base at the inner end of the lateral portion, a gear housing member integral with the bearing member, and a bearing support extending upwardly from the outer end of the lateral portion and integral 35 therewith.

6. In a base frame for elevator mechanism, a base comprising a single piece of material and including a longitudinal arm comprising an I-beam-like member and a lateral arm comprising spaced I-beam-like members, lateral riser webs integral with the arms, and means including footing members mounted on the arms in substantial alignment with the riser webs for supporting machine elements, said arms having openings located between the riser webs.

7. A base frame of the character described including a web having lateral top and bottom flanges and spaced openings, lateral riser webs integral with the body web and flanges and located between said openings, and means for supporting machine elements including a pair of footing members extending upwardly from said top flanges in substantial alignment with adjacent riser webs and integral with said flanges and webs.

8. A base frame for elevator mechanism including a longitudinal arm comprising a web having integral longitudinally spaced top and bottom flanges projecting from each

side for supporting the motor and the brake mechanism of the elevator mechanism, a pair of spaced lateral arms at one end of the longitudinal arms and integral therewith comprising webs having integral top and bottom flanges, a web integral with the outer ends of the lateral arms connecting the same and having lateral integral top and bottom flanges and riser webs on said arms integral with the same for reinforcing the flanges to provide rigid portions, and reduction gear and sheave supporting members extending upwardly from said rigid portions and integral therewith.

9. In combination with spaced supports, a base frame comprising a single metal casting including a longitudinal arm mounted on one of said supports, an arm extending laterally from said longitudinal arm having an outer end mounted on the other of said supports, and footing members on said arms including a standard at the outer end of said lateral arm.

10. A device of the character described comprising a single metal casting including an I-beam-like member having horizontal upper and lower flanges and lateral riser webs, and footing members extending upwardly from the I-beam-like member in alignment with said riser webs.

In testimony whereof I affix my signature.
